(57) **CLAIM**

The ornamental design for a file storage device, as shown and described.

DESCRIPTION

FIG. 1 is a perspective view of the file storage device according to the present invention.

FIG. 2 is a front view of the file storage device according to the present invention, the rear view being the mirror image.

FIG. 3 is a first side view of the file storage device according to the present invention, the second side view being the mirror image.

FIG. 4 is a top view of the file storage device according to the present invention; and,

FIG. 5 is a bottom view of the file storage device according to the present invention.

The broken lines are for environmental purposes only and form no part of the claimed design.
